UNITED STATES PATENT OFFICE.

WILLIAM H. THURBER, OF PROVIDENCE, RHODE ISLAND.

DESIGN FOR A SPOON.

SPECIFICATION forming part of Design No. 20,971, dated July 28, 1891.

Application filed June 20, 1891. Serial No. 397,007. Term of patent 7 years.

To all whom it may concern:

Be it known that I, WILLIAM H. THURBER, a citizen of the United States, residing at Providence, in the county of Providence and State of Rhode Island, have invented and produced a new and original Design for Spoons, of which the following is a specification, reference being had to the accompanying drawings, forming part thereof.

10 Figure 1 is a front view of a spoon showing my design. Fig. 2 is a view of the back of the upper part of the handle.

The leading feature of my design consists in the particular shape and ornamentation of the handle and the ornamentation of the bowl 15 of the spoon, as will be more fully set forth hereinafter.

In the drawings, the numeral 3 indicates the bowl of the spoon; 4, the ornamentation of 20 the bowl, consisting of a portion of the deck of a ship with a group of persons, and representing Columbus showing to his followers the New World. The stem of the handle 5 has a marginal bead 6 on each side terminating in outwardly-curved ends. From the up-

per end of the stem 5 the marginal beads 7 curve outward and then inward and inclose a bulb-shaped space. On the front of the handle, within this bulb-shaped space, an astronomical globe is represented, and on the 30 rear of the handle, in the same space, the representation of an anchor. The bulb is surmounted with the foliated ornamentation 8, and this is surmounted by the heart-shaped enlargement bordered by the curved marginal beads 9, ending in the foliated ornament 10, which forms the upper end of the handle. The heart-shaped enlargement forming the upper end of the handle and inclosed by the marginal beads 9 on the front of the handle 40 is ornamented by the bust of Columbus, and on the rear of the handle by a representation of the ship *Santa Maria*.

What I claim is—

The design for spoons, as herein shown and 45 described.

WILLIAM H. THURBER.
